CLAIM

The ornamental design for a door lock set, as shown and described.

DESCRIPTION

FIG. 1 is a top, front, right side perspective view of a first embodiment of a door lock set;

FIG. 2 is a top, rear, left side perspective view of FIG. 1;

FIG. 3 is a front elevation view of FIG. 1;

FIG. 4 is a rear elevation view of FIG. 1;

FIG. 5 is a right side elevation view of FIG. 1;

FIG. 6 is a left side elevation view of FIG. 1;

FIG. 7 is a top plan view of FIG. 1;

FIG. 8 is a bottom plan view of FIG. 1;

FIG. 9 is a top, front, right side perspective view of a second embodiment of a door lock set;

FIG. 10 is a top, rear, left side perspective view of FIG. 9;

FIG. 11 is a front elevation view of FIG. 9;

FIG. 12 is a rear elevation view of FIG. 9;

FIG. 13 is a right side elevation view of FIG. 9;

FIG. 14 is a left side elevation view of FIG. 9;

FIG. 15 is a top plan view of FIG. 9; and,

FIG. 16 is a bottom plan view of FIG. 9.

The radiating long and short lines emanating from around the perimeter region of FIGS. 1, 3, 5-9, 11 and 13-16 indicate illumination. The radiating lines emanating from the central region of FIGS. 2, 4-7, 10 and 12-15 indicate illumination. The dash-dot broken lines show portions of the door lock that form no part of the claimed design. The dot-dash broken lines represent boundaries of the claimed design and form no part of the claimed design.

1 Claim, 14 Drawing Sheets
